UNITED STATES PATENT OFFICE.

JAMES M. KERSEY, OF WELLSBURG, WEST VIRGINIA, ASSIGNOR OF ONE-HALF TO W. W. BEALL AND S. GEORGE, JR., OF WELLSBURG, WEST VIRGINIA.

SMOKE-CONSUMER.

SPECIFICATION forming part of Letters Patent No. 731,373, dated June 16, 1903.

Application filed March 12, 1902. Serial No. 97,905. (No model.)

To all whom it may concern:

Be it known that I, JAMES M. KERSEY, of Wellsburg, in the county of Brooke, State of West Virginia, have invented certain new and useful Improvements in Smoke-Consumers, of which the following is a complete specification, reference being had to the accompanying drawings.

My invention relates to smoke-consumers generally, and particularly to that class of smoke-consumers which by promoting combustion within a furnace or the like prevent the emission therefrom of smoke or other unconsumed products of combustion.

15 The object of my invention is to produce a simple and efficient device which may be readily adapted for use in any style of stove, furnace, or the like for supplying a volume of pure air to the interior of a combustion-chamber in such condition and at such a point as to produce perfect combustion therein, and thus to eliminate the objectionable outpouring therefrom of smoke or other undesirable matter.

20 In the drawings I illustrate one form of my device adapted for use in an ordinary boiler-furnace; but it should be understood that the details of construction may be widely varied to meet existing conditions which may 25 govern its installation without any departure from the spirit of my invention.

In the accompanying drawings, Figure I is a side elevation of a boiler-furnace, partly in section, showing one form of embodiment of my device adjusted therein ready for use. Fig. II is a vertical section of the subject-matter of Fig. I. Fig. III is a detail view of the lower front wall of the furnace, illustrating means for regulating the operation of my 40 device. Fig. IV is a perspective view of a portion of my device detached.

Referring to the numerals on the drawings, 1 indicates a boiler of usual type, and 2 the enveloping wall thereof. The front wall of the furnace is broken by furnace-doors 3 and ash-pit doors 4. Suitably supported by the front wall of the furnace and by a bridge 5 I provide grate-bars 6, which define between the several walls of the furnace the usual 45 combustion-chamber 7 and ash-pit 8.

50 10 indicates a pipe of suitable and preferred

size, shape, and material located within the combustion-chamber parallel with and in operative proximity to the grate-bars 6, with which, however, it does not make contact. 55 The pipe 10 communicates through the front wall of the furnace with the outside atmosphere and is there provided with a damper 11 of usual design. Extending through the combustion-chamber, the pipe 10 terminates 60 at its end opposite the front wall in a close joint with an elbow 12, which curves upward and makes a tight joint with the rounded base of a gradually-flattened head 15. The head 15 is in the form of embodiment illustrated 65 herewith fan-shaped and at its top substantially coextensive with a throat 17, defined by the top of the bridge 5 and the lower edge of a plate 18, secured to the boiler 1.

In operation the pipe 10 is so located with 70 respect to the grate-bars as, when the furnace is in operation, to be entirely surrounded by the bed of coals upon the grate-bars. By this means the pipe is, during the time that a fire is maintained within the furnace, kept 75 at white heat. Air being admitted by manipulation of the damper passes through the pipe toward the head 15, whence it issues heated to a high degree and mingle with the flame of combustion as it passes toward 80 the throat 17. It will be apparent that the heated air supplied from the head 15 is pure at the time of its mingling with the flame within the furnace, and it is by means of so supplying unvitiated air to the flame of combustion that my invention is adapted to produce 85 perfect combustion, and thus prevent the emission of smoke from the furnace.

It will be apparent that in the absence of the depending plate 18 the flame of combustion 90 and the partially-consumed products of combustion will curl around the lower curved portion of the boiler, and thus escape the positive mingling with the heated air from the head 15, which is essential in practice. 95 However, any means may be employed for forming a throat or regulating the means of egress of flame from the combustion-chamber.

Ordinarily the small amount of smoke which would escape before the pipe, elbow, 100 and head become sufficiently heated would not be considered objectionable; but, if de-

sired, means may be employed for imparting initial heat to the elbow. I illustrate one means, which consists in the provision of a door 21 in a side wall of the furnace, by 5 means of which fire may be started under the elbow and the elbow heated before the volume of smoke becomes considerable. I also show the bridge 5 as provided with a recess 10 in order that the fire-bed may be extended beyond the elbow and its proper degree 15 of heat always maintained.

It will be understood that the form of embodiment of my invention illustrated and described herewith is simply shown by way 20 of example and that the device may be varied in many ways without departing from the scope of the principle of my invention. For instance, the pipe 10 may be provided with means of steam-supply to its interior in 25 order to prevent burning out or it may be supplied with a water-jacket; but this is simply suggested as one of the many devices which in practice may be used to advantage in connection with my invention.

25 What I claim is—

1. The combination with a combustion-chamber, as of a furnace, and a bridge therein, of a fan-shaped head transversely disposed within said chamber in proximity to, but out of contact with said bridge, whereby 30 part of the products of combustion pass between said head and the bridge, and part over the head.

2. The combination with a combustion-chamber, as of a furnace, and a bridge, of a 35 fan-shaped head transversely disposed between the front wall and the bridge of said chamber, and a pipe communicating with the narrow end of said head.

3. The combination with a combustion- 40 chamber, as of a furnace, a bridge and a plate defining a throat, of a pipe-supplied fan-shaped head located in front of and in proximity to the throat.

In testimony of all which I have hereunto 45 subscribed my name.

JAMES M. KERSEY.
